ROOM PARTITIONING SCREEN

George R. Chavatet, Newport News, Va., assignor to
Newport News Shipbuilding and Dry Dock Company,
Newport News, Va., a corporation of Virginia

Filed Nov. 25, 1960, Ser. No. 62,955

Term of patent 14 years

(Cl. D13—1)

FIG. 1 is a perspective view of a room partitioning screen, showing my new design;

FIG. 2 is a longitudinal sectional view on the lines 2—2 of FIG. 1 looking in the direction of the arrows and on an enlarged scale with the central portion thereof broken away for convenience of illustration only; and

FIG. 3 is a transverse sectional view along the line 3—3 of FIG. 1, also looking in the direction of the arrows and on an enlarged scale with the central portion thereof broken away for convenience of illustration only.

The other side of the screen not shown in the drawing is substantially like the side shown.

I claim:

The ornamental design for a room partitioning screen, as shown and described.
